Inventor:

Henry Francis Brown,

By Edward Williams,

Atty.

UNITED STATES PATENT OFFICE.

HENRY FRANCIS BROWN, OF SHEFFIELD, ENGLAND.

APPARATUS FOR COOLING, HUMIDIFYING, AND FILTERING AIR OR THE LIKE.

1,271,271.

Specification of Letters Patent.

Patented July 2, 1918.

Application filed January 19, 1918. Serial No. 212,826.

To all whom it may concern:

Be it known that I, HENRY FRANCIS BROWN, a subject of the King of Great Britain, residing at Cedar Villa, Abbeydale

5 Road South; Dore, Sheffield, in the county of Yorkshire, England, have invented certain new and useful Improvements in Apparatus for Cooling, Humidifying, and Filtering Air or the like, of which the following

10 is a specification.

This invention relates to apparatus adapted for use for cooling, humidifying, filtering or otherwise treating air or other gases to be used for ventilating or other purposes.

15 Apparatus of this kind has hitherto been proposed in which a number of concentric cylinders spaced a small distance apart are arranged vertically and a sprinkler is adapted to rotate above the plates so as to wet them, the air or gas to be treated being either drawn or forced downward through the spaces between the wetted cylinders.

The present invention consists in an improvement in this type of apparatus and has 20 for its object to produce an efficient and inexpensive apparatus of this type.

The essential features of this invention consist in the arrangement of a number of approximately vertical plates conveniently 25 made of thin metal sheets, spaced apart so as to form narrow vertical substantially parallel passages arranged symmetrically about a central standard, which carries a rotating sprinkler having horizontal arms, 30 through nozzles or perforations on the under side of which the water is sprayed or dropped on to the upper edges of the vertical plates. These arms are arranged in close proximity to the upper ends of the plates, 35 and serve to close some of the passages, which are being or have just been supplied with water, for a sufficient time to allow all free water to drop through before the air again passes through them. This prevents

40 particles of moisture from being entrained with the air or gas being treated. The water which drops off the lower edge of the plates falls on to plates in the lower part of the casing and after passing through filters arranged in these plates can be utilized again 45 to treat a further supply of air or gas.

The plates and sprinkler are mounted in a suitable casing, the lower part of which forms a tank or reservoir, the whole being so constructed that the apparatus may be 55 fitted up and transported as a whole.

The accompanying drawings illustrate one form of my invention, Figure 1 being a sectional elevation and Fig. 2 a plan view of my improved cooling or filtering apparatus. 60 Fig. 3 is a detailed view on an enlarged scale of a section of the sprinkler.

In the drawings, *a* represents the casing of the apparatus which is substantially circular in plan. This casing is provided with 65 a central hollow shaft *b* secured at its lower end in a foot-step bearing *c* which may be formed integral with the casing or otherwise as desired. The upper end of this shaft is carried in a guide bearing *d* supported from 70 the casing. Secured to the upper end of the shaft are a number of hollow arms *e*, only two of which are shown in the drawing but it will be obvious that the number may be varied. These arms rotate in close proximity to the upper ends of a number of vertically arranged thin sheet metal plates *f*, only a few of which are shown in plan in Fig. 2. The plates may be either curved as shown in Fig. 2 or they may be flat or corrugated and may be arranged substantially 75 radially or substantially tangentially to the guide bearing of the vertical shaft, but I prefer to make them as illustrated with a substantially involute curve as good results 80 can be obtained with this shape of plate. They may be spaced apart in any convenient manner, as for example by securing spacing strips to them or by making small projections on the faces or by partly punching out 85 small portions which are bent outward so as to engage the adjacent plate.

The method of supporting the plates may be as shown in the drawing or it may be varied without departing from the spirit of 95 my invention. In the drawings they are shown as being carried on machined projections formed on the casing and resting on a concentric ring *g* which is supported on radial bars *g'*. The inner and outer edges 100 of the plates are preferably provided with concentric sheet metal or other linings *h*.

so as to inclose them and prevent ingress or egress of water or air from the sides. The central shaft may be driven in any convenient manner. In the example shown it is 5 driven by means of a worm wheel *k* gearing with a worm *m* on a spindle *n* driven by an electric motor *o*. This motor may also be utilized to supply water to the central hollow shaft through a rotary pump *p*, (Fig. 10 2) mounted on the motor shaft which pumps the water through a pipe *q* leading to the interior of the step bearing *c* from whence the water passes upward through the shaft *b* to the arms *e* of the sprinkler. After passing 15 through the plates the water drops on to a conical plate *r* from whence it runs to the outer edge of the casing where filters, for example gauze strainers *s*, may be located either at intervals or continuously around 20 the edge of the plate *r* to remove any impurities deposited on the wet plates from the air and washed off by the water. After passing through the filters the water accumulates in the lower part of the casing which forms 25 a reservoir and can be drawn therefrom for further use by means of the pump *p*. Suitable arrangements, not illustrated and which form no part of the present invention, should be provided for keeping the level of 30 the water in the lower part of the casing at a certain minimum height as a considerable amount of the water used will not be available for further use owing to evaporation. This may take the form of the well known 35 type of float valve inclosed in a suitable casing *y*. The upper edge of the casing is provided with an adapter *t* connecting it to a duct through which the air or other gas treated passes to wherever it is to be utilized. 40 The air is preferably drawn through the apparatus by suction entering through apertures in the side of the casing above the level of the reservoir and passes through the spaces between the plates in the opposite direction to that in which the water is traveling so that very little water will be entrained compared with what would be carried by 45 the air were both air and water traveling in the same direction and any that is entrained will fall back by gravity before reaching the duct or be deposited on the walls of the adapter from whence it will run down into the casing again.

Referring now to Fig. 3, each arm *e* is 50 provided with perforations *u* in its lower side and has, either secured to it or formed integral with it, flanges *w* and *x*. The perforations may if desired be provided with nozzles projecting downward into proximity 55 to the edges of the plates. These flanges are shown as being of unequal size, the wider flange being on the rear side in the direction of rotation of the arm. The flanges, however, may be of the same size on either

side provided that, as shown in the case of 65 flange *w*, they extend over a number of the spaces formed between the vertical plates *f*. As the spaces between the plates are small and the speed of the sprinkler arm is low, in some cases the flanges may be omitted as 70 the arm itself will act to close a number of the passages for a sufficient time to allow all free water to drop off the plates.

This, as above stated, is to insure that all 75 free water passing through between the plates will have time to drop off their lower edges before the air being treated is allowed to pass through them, leaving the plates merely wetted on the surface. For this reason the shape of the arms should substantially conform to the shape in plan of the plates so that when the plates are curved the 80 arms should be similarly curved and where the plates are radial or tangential the arm should be radial or tangential. 85

What I claim as new and desire to secure by Letters Patent of the United States, is:—

1. Apparatus for treating a gas comprising a plurality of closely arranged vertical plates inclosing substantially parallel passages through which the gas to be treated passes, a rotatable perforated sprinkler arm situated in close proximity to the upper ends of the plates, means for rotating said sprinkler arm, means for supplying water to the plates through said sprinkler arm, and means for preventing the gas being treated from passing through the spaces inclosed by plates which have just been supplied with water. 100

2. Apparatus for treating a gas comprising a casing having openings in its side walls through which the gas passes, a plurality of closely arranged vertical plates mounted within said casing, a rotatable 105 sprinkler arm mounted in close proximity to the upper ends of said plates, a motor driven hollow water conducting shaft carrying said sprinkler arm, and means for supplying water to the sprinkler arm through 110 said shaft.

3. Apparatus for treating a gas comprising a casing through which the gas to be treated passes, a plurality of closely arranged plates mounted within said casing 115 having sealed sides, a rotatable sprinkler arm mounted in close proximity to the upper ends of said plates, a hollow shaft carrying said sprinkler arm, means for supplying water to the sprinkler arm through said 120 shaft, means for driving said shaft, a reservoir in the casing from which the water is supplied to the sprinkler arm and to which it is returned after passing through the casing, and means for removing impurities 125 from the water before it returns to the reservoir.

4. Apparatus for treating a gas compris-

ing a casing through which the gas passes, a water supply therefor, a plurality of plates mounted in the casing, a rotary sprinkler mounted in close proximity to the ends of 5 the plate and having an extended surface to prevent the entraining of the particles of water with the air or gas under treatment, and means for revolving said sprinkler.

In witness whereof I have hereunto set my hand this twenty-seventh day of December, 1917.

HENRY FRANCIS BROWN.
